DESIGN FOR AN AUTOMOBILE

Gordon Miller Buehrig, Auburn, Ind., assignor to
Cord Corporation, Chicago, Ill., a corporation
of Delaware

Application May 17, 1934, Serial No. 51,828

Term of patent 7 years

To all whom it may concern:

Be it known that I, GORDON MILLER BUEHRIG, a citizen of the United States, residing at Auburn, in the county of DeKalb, and State of Indiana, have invented a new, original, and ornamental Design for an Automobile, of which the following is a specification, reference being had to the accompanying drawings, forming a part thereof:

Figure 1 is a rear perspective view showing the automobile of my new design;

Figures 2 and 3 are front and rear views respectively of the automobile; and

Figure 4 is a side view of the automobile.

I claim:

The ornamental design for an automobile substantially as shown.

Signed at Auburn, Ind., this 9th day of May, 1934.

GORDON MILLER BUEHRIG.
